CLAIM

The ornamental design for a positive airway pressure delivery console, as shown and described.

DESCRIPTION

FIG. 1 is a front perspective view of a positive airway pressure delivery console showing a first embodiment according to our new ornamental design;

FIG. 2 is front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is another front perspective view thereof;

FIG. 9 is a front perspective view of a positive airway pressure delivery console showing a second embodiment according to our new ornamental design;

FIG. 10 is front view thereof;

FIG. 11 is a rear view thereof;

FIG. 12 is a top view thereof;

FIG. 13 is a bottom view thereof;

FIG. 14 is a right side view thereof;

FIG. 15 is a left side view thereof; and,

FIG. 16 is another front perspective view thereof.

The broken lines in the drawings depict portions of the positive airway pressure delivery console that form no part of the claimed design.

1 Claim, 10 Drawing Sheets
